DESIGN FOR A COMBINED MEDICAL HAND LIGHT AND TONGUE DEPRESSOR

John A. Korengold, Chicago, Ill.

Application September 4, 1945, Serial No. 121,810

Term of patent 14 years

(CL. D83—1)

To all whom it may concern:

Be it known that I, John A. Korengold, a citizen of the United States, residing at the city of Chicago, county of Cook, State of Illinois, have invented a new, original, and ornamental Design for a Combined Medical Hand Light and Tongue Depressor, of which the following is a specification, reference being made to the accompanying drawing forming a part thereof, in which Figure 1 is a top plan view of a combined medical hand

light and tongue depressor showing my new design; Figure 2 is a side elevational view thereof; Figure 3 is a bottom plan view thereof; Figure 4 is a rear elevational view thereof; and Figure 5 is a front elevational view thereof.

I claim:

The ornamental design for a combined medical hand light and tongue depressor, substantially as shown.

JOHN A. KORENGOLD.
